No. 36,995.

Patented June 21, 1904.

UNITED STATES PATENT OFFICE.

EDGAR F. GREGG, OF THORNBURG, PENNSYLVANIA, ASSIGNOR TO
STANDARD SANITARY MANUFACTURING CO., OF PITTSBURG,
PENNSYLVANIA, A CORPORATION OF NEW JERSEY.

DESIGN FOR A KITCHEN-SINK.

SPECIFICATION forming part of Design No. 36,995, dated June 21, 1904.

Application filed December 6, 1902. Serial No. 134,203. Term of patent 14 years.

To all whom it may concern:

Be it known that I, EDGAR F. GREGG, a citizen of the United States, residing at Thornburg, in the county of Allegheny and State of Pennsylvania, have invented a new, original, and ornamental Design for Kitchen-Sinks.

My ornamental design for a kitchen-sink is shown in the accompanying drawing, in which my design is shown in perspective.

What I claim as new is—

The ornamental design for a kitchen-sink, as herein shown.
